UNITED STATES PATENT OFFICE.

EION GLASGOW ROGERSON, OF CALGARY, ALBERTA, CANADA.

MULTIPLE-FUSE PLUG.

1,316,331

Specification of Letters Patent. Patented Sept. 16, 1919.

Application filed May 17, 1918. Serial No. 235,131.

To all whom it may concern:

Be it known that I, EION GLASGOW ROGERSON, a subject of the King of Great Britain, residing at Calgary, in the Province of Alberta and Dominion of Canada, have invented certain new and useful Improvements in Multiple-Fuse Plugs, of which the following is a specification.

Electric wiring and instruments are protected and safeguarded by fuse plugs which break the circuit on the passage therethrough of an abnormal current. As generally constructed these fuse plugs are rendered unserviceable for future use after having been blown by the passage of an abnormal current therethrough.

The present invention provides a fuse plug which may be blown any number of times depending upon the number of fuse elements or wires embodied therein, such plugs being adjustable after each blow-out to bring new fuse elements and wire into operative position.

The principal object of the invention is to provide a fuse plug which may be depended upon to operate a given number of times, thereby materially reducing the cost of safeguarding electric wiring and instruments.

The invention furthermore aims to provide a fuse plug which may be utilized in the accustomed way but which contains within itself a plurality of fuse elements which are adapted to be brought successively into operative position so that when the plug is blown it is not necessary to replace the same by a new one, the same result being accomplished by adjusting the movable part so as to bring another of the fuse elements into operative position, the plug as a whole being replaceable only after all of the fuse elements have been blown.

A further purpose of the invention is the provision of a multiple fuse plug embodying means which assures the correct position of the fuse elements, this being determined both audibly and by touch.

The drawing illustrates a preferred embodiment of the invention, however, it is to be understood that in adapting the same to meet different conditions, various changes in the form, proportion, and minor details of construction may be resorted to without departing from the nature of the invention as claimed hereinafter.

55 In the drawing:

Figure 1 is a vertical central section of a

multiple fuse plug embodying the invention, the shaft and parts mounted thereon being illustrated in full lines,

Fig. 2 is a horizontal section on the line 60 2-2 of Fig. 3,

Fig. 3 is a section similar to Fig. 2 on the line 3-3 of Fig. 1, and

Fig. 4 is a like section on the line 4-4 of Fig. 1. 65

Corresponding and like parts are referred to in the following description and indicated in the several views of the drawing by like reference characters.

The plug comprises a body 1 which is hollow and of cup form, and consists of vitreous material such as porcelain. The plug is open at one end and formed with an outer flange 2 at the open end. The closed end of the plug receives a metal end 3 which constitutes one terminal of the plug. The metal shell 4 encompasses the body of the plug and constitutes the other terminal. These parts 3 and 4 may be of any well known construction. 70

A shaft 5 is centrally mounted within the plug and its lower end is stepped into the terminal 3 so as to make electrical connection therewith. The upper end of the shaft 75 13 is provided with a button or finger piece 6 of suitable material constituting a non-conductor of electricity. A cover 7 closes the open end of the plug and receives the upper end of the shaft 5. A bushing 8 is fitted in an opening centrally formed in the cover 7 and constitutes a bearing for the shaft 5. The cover 7 may be of any material, mica being preferred and is retained in place by means of a convenient ring 9 which embraces the outer flange 2 of the 80 plug. A spur wheel 10 is secured to the lower portion of the shaft 5 so as to rotate therewith, the spur or teeth of the wheel being of rounded form to admit of the shaft 5 being rotated in either direction upon the application of sufficient force thereto. A spring detent 11 cooperates with the spur wheel 10 to hold the shaft 5 in any one of the predetermined number of positions, this is effected by having the active end of the 85 100 105 detent 11 made rounding and adapted to ride upon the inclined sides of adjacent spurs or teeth so as to rest in the depression formed between such spurs or teeth. As indicated most clearly in Fig. 4 the wheel 10 is provided with eight spurs or teeth, and the plug is provided with a corresponding num-

90 95 100 105 110

ber of fuse elements or wires 12 as indicated most clearly in Figs. 2 and 3. When the active end of the detent 11 rests in the notch or depression formed between adjacent spurs 5 or teeth one of the fuse elements or wires 12 is in correct and proper position to complete the circuit through the fuse plug as indicated most clearly in Fig. 1. The detent 11 is mounted in the lower closed end of the 10 plug and may make connection with the metal end 3 thereby supplementing the action of the shaft 5 in completing the circuit. In this connection it is observed that in the event of the lower end of the shaft 5 being 15 stepped in the cup or body of the plug without making electrical connection with the metal end 3, the circuit is completed from the shaft 5 to the metal end 3, by means of the detent 11.

20 The shaft 5 is provided with a plurality of fuse elements or wires 12 which are in electrical connection therewith at one end, the opposite ends of the element 12 being electrically insulated and disposed to make 25 electrical connection with the shell or terminal 4. This result is effected by rotating the shaft 5 so as to bring the fuse elements into position to make connection with a contact 13 which is supported in the wall of 30 the plug and which is electrically connected with the shell 4 by means of a conductor 14. As indicated the fuse elements or wires 12 are embedded in an insulating material 15, the same preferably consisting of asbestos 35 or granular material of any nature which is a non-conductor of electricity. It is preferred to have the insulating material 15 loose since it is not subject to destructive influence incident to a fusing of the elements 12.

40 The provision of loose insulating material 15 necessitates the embodiment of a container for receiving and holding the same in position. This container may be of any construction and material, but it is preferred to form the same of mica, and by reason of the nature of such material the container comprises a bottom 16 and top 17 and a body or shell 18. Such container is not affected 45 by the fusing of the elements 12 hence each of such elements may be blown without affecting the usefulness of the remaining elements. The lower ends of the elements or wires 12 are connected with the shaft 5 and 50 upper ends extend through the top 17 and are flattened as indicated at 19 to insure firm connection being had with the flattened end of the contact 13.

55 A multiple fuse plug constructed substantially as herein specified is adapted for use in the well known manner. When in operative position the circuit is complete through the plug from the terminal 4, conductor 14, contact 13, fuse elements 12, shaft 5, and end 25 3. In the event of the plug blowing the

shaft 5 may be turned by means of the button or finger piece 6 to bring the connection fuse element 12 in position to make electrical connection with the contact 13 when the circuit through the plug will be the same as 70 hereinbefore described. When the next element 12 is blown the plug may again be adjusted to bring another of the fuse elements into operative position. It will thus be understood that the plug may be adjusted for 75 use as many times as it contains fuse elements 12. When turning the shaft 5 a click is made audible by the passing of the detent 11 from one notch or depression to the other and in addition the proper positioning of 80 the fuse elements is made known by the sense of touch. The fuse elements 12 are so disposed that when the detent 11 rests in the depression or notch formed between adjacent spurs or teeth of the wheel 10, one of 85 such fuse elements is in position to make the connection with the contact 13, thereby completing the circuit in the manner herein stated.

90 The foregoing description and the drawings have reference to what may be considered the preferred, or approved, form of my invention. It is to be understood that I may make such changes in construction and arrangement and combination of parts, 95 materials, dimensions, et cetera, as may prove expedient and fall within the scope of the appended claims.

Having thus fully described my invention, what I claim as new and desire to secure by Letters Patent is:—

1. A fuse plug, comprising a hollow body, contacts mounted on the body and electrically insulated from each other, a shaft mounted in the body and electrically connected with one of said contacts, fuse elements carried by and grouped about the shaft and in electrical connection at one of their ends therewith and having their opposite ends spaced apart and electrically insulated from one another and adapted to be brought successively into engagement with the remaining contact of the body, a fuse-positioning member rotatable with the shaft, and a detent coacting with the fuse-positioning member.

105 2. A fuse plug, comprising a hollow body, a fixed contact associated therewith, a shaft rotatably mounted in the hollow body, and a plurality of fuse elements grouped about the shaft and in electrical connection at one end therewith, said fuse elements adapted to be successively brought into electrical connection with the said fixed contact by rotation of the shaft, and means coacting with the body of the plug and shaft for properly fixing the position of the fuse elements when adjusting the shaft, the same consisting of a spur wheel and a spring actuated detent.

110 3. A fuse plug, comprising a hollow body,

terminals mounted on the body and electrically insulated from each other, a fixed contact in electrical connection with one of the terminals, a shaft rotatably mounted in the body, and in electrical connection with the remaining terminal, and a plurality of fuse elements mounted on the shaft and adapted to be successively brought into position to make electrical connection with the said fixed contact, a spur wheel rotatable with the

shaft, and a spring actuated detent mounted upon the body, and coacting with the spur wheel, to properly position the fuse elements.

In testimony whereof I affix my signature in presence of two witnesses.

EION GLASGOW ROGERSON.
